(57) CLAIM

The ornamental design for vehicle wheel rim, as shown and described.

DESCRIPTION

FIG. 1 is a front perspective view of a vehicle wheel rim according to the present invention;

FIG. 2 is a left side view of the vehicle wheel rim according to FIG. 1, the right side view being a mirror image of the left side view and the top and bottom views being identical to the left and right side views;

FIG. 3 is a front view of the vehicle wheel rim according to FIG. 1;

FIG. 4 is a rear view of the vehicle wheel rim according to FIG. 1; and,

FIG. 5 is a left side sectional view of the vehicle wheel rim according to FIG. 1 taken along line 5—5 of FIG. 3.

The broken line showing of the spokes in FIGS. 1 and 3-5 is for the purposes of illustrating environment and forms no part of the claimed design.
